UNITED STATES PATENT OFFICE.

GORDON CAMERON, OF WOLLASTON, MASSACHUSETTS, ASSIGNOR TO SEARS B. CONDIT, JR., OF BROOKLINE, MASSACHUSETTS.

OIL SWITCH.

1,427,442.

Specification of Letters Patent. Patented Aug. 29, 1922.

Application filed August 2, 1918. Serial No. 247,930.

To whom it may concern:

Be it known that I, GORDON CAMERON, a subject of the King of Great Britain, residing at Wollaston, in the county of Norfolk and State of Massachusetts, have invented an Improvement in Oil Switches, of which the following is a specification.

My invention relates to oil switches.

It is common practice to construct the frames of oil switches of cast iron or other magnetic material, for use when the current controlled by the switch does not exceed a certain moderate amount, in which case the cast iron frame serves satisfactorily to support the switch structure and does not heat unduly. When, however, current densities in excess of this limit are used, the eddy current and hysteresis losses in the iron frame are very appreciable, and cause the frame to become unduly heated. For this reason the supporting frame for the switch structure is usually made of a non-magnetic material such, for instance, as brass or some other alloy. The non-magnetic material, which must of necessity be employed, is however relatively costly in comparison with cast iron, and it is therefore desirable that no more of this alloy be used than is necessary.

The supporting frame is usually formed of a flat plate structure from which the oil receptacle depends, and through which the switch leads are inserted to make connection with the switch contact members immersed in the oil of the container or containers. A supporting bracket is usually integrally formed with the flat supporting plate, by means of which the switch structure may be secured to a convenient support. Inasmuch as the eddy current and hysteresis losses occur in the immediate vicinity of the switch leads as they pass through the plate, it serves no good purpose to form this extended bracket of non-magnetic material, as it is relatively unaffected by the current in the switch leads and component parts of the switch structure.

Consequently, an object of my invention is in the provision of a supporting plate for the switch structure formed of non-magnetic material by means of which the various losses due to high current densities may be reduced, and to form the supporting bracket for the plate separate from the plate and of a relatively cheap metal such as cast iron,

and to secure the bracket and the plate together as a single unit by any convenient means. By this means I provide non-magnetic material only where it is needed, and form other parts of the structure of magnetic material, such as cast iron, thus reducing the cost of the supporting plate to a minimum, and at the same time providing adequate protection against losses due to high current values in the switch structure.

A further object of my invention is to secure the operating members of the switch to the separate switch frame supporting bracket, whereby the alloy switch frame is free from all links or levers that may be employed to move the switch brushes. Such an arrangement has as advantage in that but one size of bracket need be employed for several different sizes of switches, whereby the cost of the switch supporting structure is considerably reduced over the cost of a switch supporting structure in which the bracket is integrally formed with the supporting plate.

With a switch of the type described, in which the component parts of the switch structure are arranged on and depend from a supporting plate into a receptacle for oil suspended beneath the plate, said plate being provided with an extended bracket by means of which it may be secured to supports, it is desirable that provision may be made for mounting the switch either on the back of a flat panel or against a flat wall, or from a supporting structure formed of pipes.

Heretofore it has been customary to form the switch frame with a flat face whereby it may be firmly supported against a flat structure such as a switch panel or wall. To mount the switch upon a pipe structure, it has been necessary to employ a grooved intermediate plate between the bracket and the pipe structure, the grooves being of such shape as to partially surround the pipes composing the structure, said plate also having a flat face to engage with the corresponding flat face of the bracket.

A further object of my invention is in the provision of the bracket of a switch with a flat portion, whereby it may be arranged against and secured to a flat wall or other supporting structure, and to also provide said bracket with grooves, whereby the bracket may be arranged upon a pipe struc-

ture without the use of other supplementary parts.

In the commercial operation of switches of the type described it is often not practical to mount the switches adjacent the operating handles therefor, and whereas it is sometimes possible to arrange the switches on the back of a switch board and extend an operating link from the switch handle 10 on the face of the board, through the board to the switch operating members, yet it is also desirable and necessary that the switch may be arranged on supports remote from the operating handle, either on a wall or 15 on the floor, and the operating handle may be in the same room or in a room above or below the switch, and links or rods must be extended between the operating handle and the switch operating members.

20 The operating members, must, therefore, be arranged to operate the switch when the link connecting the members with the operating handle extends downward from above, upward from below, or directly in 25 line with the operating members. In the provision of the operating members for the switch arranged for operation from any convenient position, it has heretofore been necessary to provide special parts for the switch 30 operating structure, which can only be used with a certain direction of movement of the operating link or rod, and must be removed and replaced by others of different form or structure for operation from a rod movable in another direction. This results in 35 the necessity for keeping in stock a number of various parts of the switch operating structure which are comparatively infrequently used, and which, when the switch 40 is installed, may become lost and cannot be easily replaced.

Consequently, a further object of my invention is in the provision of switch operating members which are capable of transmitting movement of the operating rod from any of the three above mentioned directions to the movable members of the switch to cause their proper operation, whereby there is no necessity for interchange and substitution of various parts of the switch operating members.

Fig. 1 is a side elevation of an oil switch embodying my invention.

Fig. 2 is a plan view of Fig. 1.

55 Fig. 3 is a detail of the switch bracket and operating mechanism arranged for operation from a horizontal direction.

Fig. 4 is a detail of a switch operating member arranged for operation from a point below the switch.

Fig. 5 is a detail of the switch bracket and operating mechanism arranged for operation from a point above the switch.

60 Fig. 6 is a plan view of the switch support bracket.

Fig. 7 is an end view of the switch plate.

As here shown, the switch is arranged and supported from the switch plate 10, which may be formed of a non-magnetic material such as brass or other alloy. The 70 stationary switch elements 11 are arranged on insulated bushings 12 beneath said frame 10, and extend beneath the oil contained in the separate oil containers 13. Said containers are suitably supported by bolts 75 14 from the switch plate 10, and said plate thereby forms a cover for the oil receptacles.

The stationary switch members 11 are arranged at the extremity of switch leads 15, which extend through the switch plate 10 and are insulated therefrom by suitable bushings 16. The movable switch elements or brushes 17 are arranged in the oil receptacles beneath the stationary switch members, and are arranged on insulating rods 18 depending from a common cross bar 19 arranged above the supporting plate 10. Said bar 19 is provided with lugs 20, by means of which connection is made to the 90 switch operating members.

The supporting plate 10 is formed with strengthening ribs 21, which unite to form an upright portion 22 to which the supporting bracket 23 is arranged to be secured. 95 Said bracket is flanged for strength, and comprises a flat portion 24 adapted to be secured to the corresponding portion 22 of the plate 10 by means of suitable bolts 25, and is also formed with a foot portion 26. 100

Said foot portion 26, as here shown, is formed with two flat faces 27, by means of which the bracket and switch may be securely fastened to a flat surface, as indicated at 28, which may be a wall or switch board. Said flat portions 27 are also formed with 105 grooves 29 therein, which are adapted to receive and partially surround the pipes 30 of a frame structure, to which it is adapted to be secured by bolts 31.

110 By the provision of the foot portion 26 with a flat surface and also with a groove portion, the switch may be mounted either upon a flat switch board or wall, or upon a pipe structure without the necessity for 115 the employment of any auxiliary parts or members. Two parallel spaced apart flanges 32 serve to connect the foot portion 26 with the flat portion 24 of the bracket, and links 33 are pivoted thereto by pin 34, and extend 120 to the ears 20 on the switch bar 19, and are pivotally secured thereto by the pin 35.

The switch bracket is formed with a lug 36, which extends from the flat portion plate, and a link 37 of a toggle is pivoted thereto 125 at 38. The other link 39 of said toggle is pivoted to the link 33 at 40, and said links are pivoted together at 41. Said toggle forms means whereby the links 33 may be moved about their pivot 34, to move the 130

movable switch members 17 into or away from contact with the stationary switch members 11.

The switch operating member, formed of two flat plates 42, shaped in substantially triangular form, is pivoted to the bracket 23 by means of the pin 43, and is maintained in position on said pin between the flanges 32 of said bracket by means of spacing washers or rollers 44. A link 45 is connected by means of a pin 46 to said operating member 42, and the other end of said link is connected by the pivot 41 to the toggle. A movement of said operating member 42 thereby serves to move said toggle to operate the switch members.

Said operating member 42 is provided with two holes 47 and 48 therein, by means of which connection may be made to the plate with an operating rod extended between the switch and the switch operating handle, remotely positioned from the switch.

As shown in Figs. 1 and 3, the operating rod 49 is secured by a suitable pin in the hole 48 of the operating member, and is arranged for horizontal movement. A movement of said rod to the right in Fig. 1 serves to straighten the toggle formed of links 37 and 39, to thereby move the link 33 into position shown in the dotted line of Fig. 3, to move the members 17 into contact with the stationary switch members, to thereby close the switch. A movement of said rod 49 to the left serves to open the toggle to permit the movable switch members to return to their open position.

When the switch operating rod 49 is extended upwardly from beneath the switch structure, connection is made with the operating member 42 at 47, as shown in Fig. 4, instead of at 48, as previously described. When connected in this manner a downward movement of said rod 49 serves to straighten the toggles to thereby close the switch, and an upward movement of said rod serves to open the switch. When the operating rod 49 is downwardly extended from above the switch, said operating member 42 is disconnected from pivotal engagement with the bracket 23 by the removal of the pivot pin 43, and said member is reversed in position and again pivoted to said bracket by means of a pin extended through holes 50 in said flanges 32, as shown in Fig. 5.

The downwardly extended operating rod 49 is then pivoted at 47 to said member 42. In this arrangement an upward movement of the said rod 49 serves to move the switch operating mechanism into the position shown in the dotted line to close the switch, and a movement of the rod in a reverse sense causes the operating mechanism to open the switch.

With the provision of the operating mem-

ber 42 arranged with means for connecting the switch operating rod thereto at different points, and with means whereby the operating member may be changed in position with respect to the toggle, whereby the direction of movement of the link 45 connecting the plate with the toggle may be reversed relative to the movement of the switch rod 49 in its various positions to close the switch, it is seen that but a single operating member 42 is required to provide means whereby the switch may be operated by an operating rod extended from the switch in any desirable direction.

I claim:

1. In an electric switch, a switch supporting member having a portion adapted to support the component parts of the switch and an extended bracket portion formed of a material dissimilar to that composing said supporting portion, said bracket portion being independent of the supporting portion of said member but secured thereto to form a unitary switch supporting member.

2. In an electric switch, a switch supporting member having a portion formed of non-magnetic material adapted to support the component parts of the switch and having openings therethrough for the passage of the switch leads, and an extended bracket portion by means of which the switch may be secured to a support, said bracket portion being formed of a material dissimilar to that composing said supporting portion and independent of the non-magnetic portion but secured thereto to form a unitary switch supporting member.

3. In an electric switch, a switch supporting member having a substantially flat portion formed of a non-magnetic material adapted to support the component parts of the switch and an extended bracket portion formed of a material dissimilar to that composing said supporting portion secured thereto to form a unitary switch supporting member.

4. An electric switch having operating mechanism including an operating member arranged for movement in one direction to close the switch and in the opposite direction to open the switch, a second member arranged to be connected with said first member in a plurality of angularly different positions also arranged for connection with an operating rod in a plurality of angularly different positions with respect thereto, whereby to actuate said first member in the same direction to operate the switch from all positions of said operating rod.

5. An electric switch having operating mechanism including an operating member arranged for movement in one direction to close the switch and in the opposite direction to open the switch, a second member arranged to be connected with said first mem-

ber in a plurality of angularly different positions also arranged for connection with an operating rod at a plurality of different points thereon whereby to actuate said first member in the same direction to operate the switch from different angular positions of said operating rod.

6. In an electric switch, a bracket adapted pivotally to support a member of the switch-operating mechanism at a plurality of places on it, and switch-operating mechanism including a member arranged for removable pivotal connection with said bracket at a plurality of places on said member also arranged for removable pivotal connection at a plurality of places on it with an operating

rod, whereby said member may be disconnected from said bracket and re-arranged and again pivotally connected thereto in a different position and the operating rod disconnected and re-connected from a different angle to said member in its re-arranged position and the switch arranged for operation.

In testimony whereof, I have signed my name to this specification, in the presence of two subscribing witnesses.

GORDON CAMERON.
